DE WITT M. O'NEILL ET AL
OIL AND GAS SAVING AND LIFE SAVING COLLAR
FOR OIL AND GAS WELL DRILLING OUTFITS
Filed May 14, 1925

FIG. 2.

FIG. 1.

De Witt M. O'Neill
Sherman M. Brown INVENTORS.

BY *Loyall J. Miller*

ATTORNEY.

UNITED STATES PATENT OFFICE.

DE WITT M. O'NEILL AND SHERMAN MCKOWN, OF YALE, OKLAHOMA.

OIL AND GAS SAVING AND LIFE-SAVING COLLAR FOR OIL AND GAS WELL DRILLING OUTFITS.

Application filed May 14, 1925. Serial No. 30,274.

To all whom it may concern:

Be it known that we, DE WITT M. O'NEILL and SHERMAN MCKOWN, citizens of the United States, residing at Yale, in the county of Payne and State of Oklahoma, have invented a certain new and useful Improvement in Oil and Gas Saving and Life-Saving Collars for Oil and Gas Well Drilling Outfits, of which the following is a specification, reference being had to the accompanying drawings.

Our invention relates to improvement in oil and gas saving, and life saving collars for drilling well outfits.

15 The object of the invention is to provide a device of this character which will be easily and economically made and installed, prevent the spontaneous overflowing of the well and its voluntarily blowing itself in, 20 and checks and holds the flow of the oil and gas until the rig can be cleared of those around it, and give time to prepare for the care of oil and gas when the flow is permitted to come from the well; prevents damage to the rig and tools, prevents the maiming and killing of employees and others around the rig, prevents the loss of oil and gas incident to said overflowing and blowing in, prevents damage and loss from fire, permits the putting in and taking out and changing of tools at any time the control head and hole may be open.

25 The invention, novel features, details of construction, and combination of parts, and other objects of the invention will be hereinafter more particularly set forth, illustrated in the one-page drawing, and pointed out in the appended claim.

Reference hereby made to the drawing 30 forming a part of this application, of which,

Figure 1 is an elevation view of the device showing the ordinary and usual parts used in connection with it.

Figure 2 is a sectional perspective view of 35 a portion of the device.

Like characters of reference designate like parts in all the figures.

40 The device consists of a heavy collar 9, as described, of suitable material, used ordinarily in connection with the usual nipple 1, the usual clamp 2 holding members 3, 4, an ordinary and usual collar 5 thereabove, the usual nipple 6 connected therewith at one end, and at the other connected with the

device 9, an ordinary and usual nipple 7 55 connected at one end to said device thereabove and at the other end to the ordinary and usual control head 8. All of these parts except the device 9 are not claimed in this application as invention except as they may be used in connection therewith.

The device 9 consists of a cylindrically shaped thick heavy collar of suitable material helically threaded at the lower end 12 and at the upper end 13 connecting with a nipple 6 therebelow and a nipple 7 thereabove, each helically threaded to fit said device 9 at 12 and 13. There is a plurality of larger ports entering said device at the periphery 14 helically threaded and extending a distance into the wall of said device approximately half way therethrough 15. A smaller and reduced sized port 18 on each of said larger ports 14 extends from the inner end of said larger port 15 inwardly and downwardly therefrom through the inner wall of said collar as shown at 19, connecting with said port 14 are steam connections 16, 17.

50 In practically every oil and gas field much loss has been entailed by wasting oil and gas, losing tools, and many oil field workers have been maimed and killed by the sudden and unexpected gushing and flowing of the wells. Many attempts have been made to stop and prevent this, all of which have failed, by being impractical and inadequate.

55 It will be observed by connecting up the device on the drilling outfit at 14 with steam pressure always present in the field the port 14 up to 15 being larger than the port 18, 19, forces the steam through a smaller aperture at a tremendous pressure into the inside the casing and down into the well, thereby checking and stopping any escape of either oil or gas from the well, holding it entirely back and within control so as to allow for the preparing for taking care of the product of the well, and escape of those endangered by the otherwise gushing and overflowing of the well. The walls 10 of the device being thick and heavy, much thicker and heavier than the casing in the well allow great pressure to be used thereon by the steam, and the ports being made permanently into the 60 walls, and extending inwardly and downwardly gives the steam a downward direction into the well, and being thus confixed

by the casing in the well and the walls of the hole itself permits the steam to be introduced far down into the well and by its weight, moisture and force prevents the outflowing of the gas or oil from the well until such time as it is desired to permit same to flow.

From the description of the one page accompanying drawing and specification the advantages of the operation, making, construction and application of the device will be apparent to those skilled in the art to which our invention pertains; but it will be understood that any modifications within the scope of the claimed invention may be made in the making, constructing, operation and application without departing from the principle of the invention, or sacrificing any of its advantages.

Having thus described the invention, what is claimed and desired to be secured Letters Patents, is:

In a device of the character described, a heavy cylindrical collar, means securely connecting the same to a nipple below and a nipple above, the said collar being placed above the usual clamp and the usual collar and below the usual control head of a well drilling outfit, a plurality of larger ports leading from the periphery of the collar to a point midway the wall thereof, a similar plurality of smaller ports leading from the inner end of the larger ports and extending inwardly and downwardly therefrom and through the inner wall of said collar.

DE WITT M. O'NEILL.
SHERMAN McKOWN.
